(57) **CLAIM**

The ornamental design for a nut retainer, as shown and described.

DESCRIPTION

FIG. 1 is an isometric view of a top, front, and right side of an ornamental design for a nut retainer;
FIG. 2 is an isometric view of a bottom, rear, and left side of the nut retainer of FIG. 1;
FIG. 3 is a front elevational view of the nut retainer of FIG. 1;
FIG. 4 is a rear elevational view of the nut retainer of FIG. 1;
FIG. 5 is a right side elevational view of the nut retainer of FIG. 1;
FIG. 6 is a left side elevational view of the nut retainer of FIG. 1;
FIG. 7 is a top plan view of the nut retainer of FIG. 1; and,
FIG. 8 is a bottom plan view of the nut retainer of FIG. 1. The dash-dash-dash broken lines are included for the purpose of illustrating portions that form no part of the claimed design.

1 Claim, 7 Drawing Sheets
